FIG. 10 is a front view of a second image in the sequence according to the second embodiment;
 FIG. 11 is a front view of a third image in the sequence according to the second embodiment;
 FIG. 12 is a front view of a fourth image in the sequence according to the second embodiment;
 FIG. 13 is a front view of a fifth image in the sequence according to the second embodiment;
 FIG. 14 is a front view of a sixth image in the sequence according to the second embodiment;
 FIG. 15 is a front view of a seventh image in the sequence according to the second embodiment; and,
 FIG. 16 is a front view of an eighth image in the sequence according to the second embodiment.

The peripheral broken rectangle depicts a display screen or portion thereof and forms no part of the claimed design. All other broken lines show portions of the graphical user interface and form no part of the claimed design. The oblique lines shown in FIGS. 9-16 represent a contrast in appearance and form part of the claimed design. All white space forms no part of the claimed design.

The appearance of the transitional image sequentially transitions between the images shown in FIG. 1 to FIG. 8 in the first embodiment and from FIG. 9 to FIG. 16 in the second embodiment.
